CLAIM

The ornamental design for a decorative music stand plate, as shown and described.

DESCRIPTION

FIG. 1 is a front view of a decorative music stand plate showing my new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof; and,

FIG. 8 is a front view of a second embodiment of a decorative music stand plate; the remaining view being identical to those in FIGS. 1 through 7.

The broken lines showing are for the purpose of illustrating the environment of the article only and form no part of the claimed design.

1 Claim, 4 Drawing Sheets

FIG. 2

FIG. 7

FIG. 8
